LAWN SPRINKLER

John D. Beinert, Babylon, N.Y., assignor to Melnor Industries, Inc., Carol Place, Moonachie, N.J., a corporation of New York

Filed July 21, 1960, Ser. No. 61,482

Term of patent 7 years

(Cl. D91—1)

FIG. 1

FIG. 2

FIG. 3

FIG. 4

FIG. 5

FIG. 6

FIG. 1 is a top plan view of a lawn sprinkler showing my design;

FIG. 2 is a side elevational view thereof;

FIG. 3 is an end elevational view thereof, on an enlarged scale, as seen from the right in FIG. 1;

FIG. 4 is an end elevational view thereof, on an enlarged scale, taken along the line 4-4 of FIG. 2;

FIG. 5 is an end elevational view thereof, on an enlarged scale, seen from the left of FIG. 1; and

FIG. 6 is a cross sectional view taken along the line 6-6 of FIG. 3.

The dominant features of my design reside in the portions shown in full lines.

I claim:

The ornamental design for a lawn sprinkler, as shown and described.
